UNITED STATES PATENT OFFICE.

ERNEST PENBERTHY, OF REDRUTH, CORNWALL, ENGLAND, ASSIGNOR TO THE CLIMAX ROCK DRILL & ENGINEERING WORKS LIMITED, OF LONDON, ENGLAND, A COMPANY OF GREAT BRITAIN.

PERCUSSIVE ROCK DRILL.

Application filed March 24, 1927, Serial No. 178,022, and in Great Britain April 21, 1926.

This invention relates to percussive rock drills and has for its object to provide an improved method of retaining and holding the valve bushings against movement.

5 According to the present invention the valve bushings are retained and held from movement at one end by means of a division ring and at the other end by the cover for the cylinder of the hammer piston, said ring 10 and cover being for this purpose preferably provided with projections engaging with corresponding shoulders on the valve bushings.

An example of construction in accordance with the invention is illustrated in the accompanying drawings wherein

Figure 1 shows a longitudinal section of a percussive rock drill with the invention applied thereto, and

Figure 2 shows a section on the line 2—2 20 of Figure 1.

According to one example of construction as applied to pneumatic rock drills, valve bushings 20, 21 are fitted into the ends of the valve casing 7 and the bushing 20 at one 25 end is held in position and prevented from displacement by a projection 27 formed on the division ring 28 which is located between the cylinder 10 of the hammer piston 11 and the guide 29 for the drill 30. The projection 27 on this division ring 28 when in 30 position engages with a shoulder portion 31 on the valve bushing 20 and thus prevents

any rotation thereof. The valve bushing 21 at the other end of the valve chamber 7 is held in position by means of the cover plate 35 32 for the end of the cylinder 10 of the hammer piston 11 which is also provided with a shouldered projection 33 adapted to engage with a corresponding shoulder 34 on the valve bushing.

Having thus described my invention what I claim as new and desire to secure by Letters Patent is:—

In a percussive rock drill a hammer cylinder, a valve chamber mounted on said hammer cylinder, two bushings fitted one into each end of said valve chamber, shoulders on said bushings, said shoulders having an engaging face extending in a plane at right angles to the longitudinal 45 axis of the bushings and at an angle to the horizontal, an annular dividing ring at one end of said hammer cylinder, an annular end cover on the other end of said hammer cylinder, and projections, one on the said 50 dividing ring and one on the said end cover, said projections extending laterally from said dividing ring and said end cover, said 55 projections having engaging faces, which are complementary to the engaging faces of the shoulders and co-operate therewith for the 60 purpose of retaining the bushings in position and preventing movement thereof.

ERNEST PENBERTHY.
